DUPLICATING METHOD AND MEANS

David Wolfson, Far Rockaway, N. Y.

Application November 10, 1936, Serial No. 110,071

10 Claims. (Cl. 101—133)

The present improvements relate to methods of duplicating graphic matter carried by a master copy or sheet and means for practicing the same. Primarily they involve a new method of duplication and secondarily mechanical means which embody the best mode at present devised for practicing and applying the principles of that method; and while such means are believed to be of great value and importance, the method or process may be practiced by other mechanical means or by hand aided only by very simple mechanical devices.

The principal object of the improvements is to provide a method and means for duplicating through the use of copying ink or the like matter carried by or stencilled in a master sheet on copying sheets by simple and effective operations and efficient, durable and simple mechanism, and to insure a clear and clean transference of the original to a maximum number of copies quickly and easily, with a minimum of force and pressure and without unnecessary wear on the copy or wastage of materials.

The mechanism of the preferred embodiment is in part an improvement in that described and shown in my copending application Serial No. 36,464, filed August 16, 1935, to which reference may be had for further illustration and description of corresponding parts.

30. The improvements are illustrated in the accompanying drawings, which show an exemplary embodiment in a machine for practicing the new method, and in which—

Fig. 1 is a longitudinal vertical section of such a machine;

Fig. 2 is a transverse vertical section of the same substantially on the line 2—2 of Fig. 1, looking in the direction indicated by the arrows in that figure;

Fig. 3 is an enlarged sectional view of the master copy, supporting plate therefor, copying sheet and fragments of the upper and under printing pressure rollers, in operation;

Fig. 4 is an enlarged detail partly in vertical section of the reservoir for the volatile moistening fluid and means for mounting the same and regulating the fluid supply; and

Fig. 5 a plan, partly in section, of the said machine.

50. The frame of the machine consists essentially of feet 1 with side portions 4 and 5. Longitudinal side tracks 6 and 7 are mounted at their ends in the end portions of the frame and on them travel the slides 8 and 9, supporting the carriage for the working parts of the machine.

Cross bars 2 and 3 are rigidly secured at their ends in opposite ends of the frame members 1 and 2 and connect the same to form a rigid supporting structure.

The supporting sheet or flexible bed plate 10 extends lengthwise of the machine and is supported at one end by tension springs 11 connected therewith and with the end bar 2 and by a sheet metal hook 12 passed over the opposite end bar 3 to which the said supporting sheet is 10 soldered or otherwise secured. The supporting sheet is therefore suspended and held under lengthwise tension. It is not necessary, however, for most purposes to employ the spring 11, although this spring adds to the flexibility of the 15 sheet and provides a mounting therefor which permits it to be quickly and easily placed in position or removed. Sheets of different thickness and material and various degrees of flexibility may be used as made necessary by the character 20 of the work and the master sheet employed. If stencil work is to be done, a foraminous supporting sheet will be used with a flannel sheet supported thereon and the copying sheet applied to the stencil on the top surface of the flannel sheet, 25 so that ink applied to the under side of the supporting sheet will pass therethrough, through the intervening flannel sheet and the stencil to make the desired impression on the copy sheet.

The master copy sheet 17, which in the present 30 embodiment may be assumed to be a sheet of paper with the master copy thereon in reverse, lies flatwise on the supporting sheet or plate 10 and is held against movement in the direction of the travel of the carriage and rollers in making 35 a copy by a clip 13 consisting of a folded strip of sheet metal, by having its forward edge turned in between the folded portions of the clip as indicated at 14. To bind this edge of the master sheet in the clip a small metal plate 15 may be 40 forced in between it and the lower fold of the clip so as to have a wedging action, and this wedging plate is preferably attached to the lower part of the hook plate 12 by means of a chain 16 connected with both.

The sheet 10 is not only a supporting sheet 45 for the master copy but operates in a peculiar manner in the making of the impression on the copying sheet. To this end it is preferably made of relatively thin sheet metal, a thickness or gauge of .016 inch or a little less being suitable. It should have a hard, smooth surface and a resilient body of spring tempered brass, German silver, nickel silver or similar metal. Thin, hard rolled paper board may be used, but 50 55

this has not been found to possess the desired durability. It will be observed that a sheet of the character indicated is flexible so that when an impression is being made it will flex under the pressure of the rollers and conform to a slight extent to the curvature of the lower and harder roller, thus giving a relatively sharp line of pressure across the master and copy sheets, which insures a clear and sharp impression of the matter being duplicated. After passing between the rollers the sheet 10 instantly returns to its original planular form, and as it is made of material having great tensile strength it does not stretch while the impression is being made and thus cause blurring of the transfer impression.

The upper roller 18 is mounted in the carriage which consists of a cross plate 20 pivotally mounted in the slides 8 and 9 at 21 and the longitudinal members 22 extending from either side of the cross plate in which the roller 18 and also the moistening and idler feeding roller 23 are mounted. The cross member 24 mounted separately and rigidly on the slides 8 and 9 is also a part of the carriage structure, and the lower roller 19 is mounted for rotation in brackets 25 rigidly connected with and depending from the slides.

The handle 26, by which the carriage is operated, extends upwardly from the cross member 27 connecting the outer portions of the arms 22, and these arms may therefore be depressed, carrying the rollers 18 and 23 with them, by this handle, so as to cause pressure between the upper and lower rollers during the printing operation. A spring 28 normally holds these parts in their uppermost position in which the handle is stopped by the rigid cross member 24, the depression of the handle and rollers being against the tension of this spring. Secured between the arms of the handle and spaced below the hand grip 26' thereof is a curved plate 29, which turns the sheet backward and downward after it has been printed and prevents it from coming in contact with the hand of the operator.

On each side of the carriage curved spring guides 30 for the printing sheet are mounted by having their upper ends fixed to the ends of the arms 22, as shown at 31, and these guides extend downwardly and then horizontally between the shafts 18' and 19' of the rollers 18 and 19 so as to guide the printing sheets between the rollers and strip them from the master copy after they have been printed. As the printing sheets are wider than the rollers and the master copy, to provide the usual side margins of the printed sheet, they will be engaged by guides 30 beyond the ends of the rollers, and therefore the guides are located beyond the pressure surfaces of the rollers at each side, and are so arranged as to engage the under side of each printing sheet near its side edges so as to separate it from the master copy as it is printed and guide it upwardly to the open space at the rear of the carriage.

The upper roller 18 is greater in diameter than the under roller 19, and has a rigid core 18'' with a relatively soft, thick cover 18''' thereon of rubber or some composition having similar properties. The under roller is of the same character except that the cover 19''' is of relatively hard vulcanized rubber or like material. The effect of this construction and composition of the rollers is that when the upper roller is pressed down against the lower roller, through the sheets,

it is slightly flattened along the line of pressure between the rollers, and even caused to become slightly concave at that line (see Fig. 3) following the contour of the harder under roller to a certain extent. The supporting sheet is also flexed slightly, as are also the master copy and the printing sheet. This accomplishes a number of important results, including the prevention of slippage and the production of a rather sharp line of maximum printing pressure. It also gives the upper roller a satisfactory traction grip on the back of the printing sheet. Thus, the operation of the parts which produce the duplication are made positive and accurate in their operation.

The clear printing sheets 32 are fed by the feeding chute and guide 33, mounted on the carriage, to the rollers 18 and 23 and as the carriage is moved forward the rotation of these rollers feeds the sheet past the guide 34 to the bite of the rollers 18 and 19 as they pass over the sheet 10 and master copy and exert pressure thereon, and as it is printed it passes up over the guide 30.

The means for moistening the under surface of the sheets comprises a holder 35 mounted on the cross member 20 of the carriage and provided with a cover 36 secured by a bolt 37 and hand nut 38, a filling of loose absorbent material 39 and a bottle 40 for the liquid mounted on the cover, also an absorbent gravity conductor 41. The bottom 42 of the holder 35 is inclined upwardly from its lower transverse edges and divides the holder into two compartments open to each other. The forward compartment receives the liquid from the bottle, which is absorbed by the loose material 39 and the rearward compartment receives the conductor 41 which is held therein by the partition 43 depending from the cover and the upstanding flat lugs 44 near the apex of the bottom 42. The liquid conductor 41 is preferably of closely felted material and extends through a longitudinal slot 35' at or near the bottom of the holder 35 beyond the holder and into contact with the combined moistening and feeding idler roller 23. The liquid saturates the conveying sheet 41, and passes slowly over it to the roller 23 with the upper surface of which it is in contact, and this roller 23 distributes it evenly over the sheet 32 so as to moisten the sheet on the side to be printed; and as the rollers 18 and 23 are in close contact no excess liquid can pass through between them. It will be understood that the outer layer of the roller 23 is of vulcanized rubber or similar material having a certain degree of resiliency, but harder than the outer cover or layer 18'' of the roller 18.

The bottle reservoir 40 has its exteriorly threaded neck 45 threaded into the interiorly threaded upstanding collar 46 on the cover (see Fig. 4) and is provided with a conical valve plug 47 in its mouth around which the liquid passing from the bottle flows slowly when the valve plug is not seated in the seat 48 of the feed opening 49 of the cover 36. The rate of flow of the liquid from the bottle into the holder 35, and the resulting rate of flow to the roller 23, may be regulated by rotating the bottle 40 so as to increase or decrease the opening between the valve plug 47 and its seat, or it may be cut off entirely, so that no liquid will escape when the machine is not in use.

A paper holder 50 is removably mounted in the lugs 51 of the holder 35 by means of pins 52

adapted to be passed into small vertical holes in the said lugs.

In operation, the master copy is placed on the supporting sheet 11 and secured in position with its printing face up. A plain sheet to be printed is then placed in the feeding chute with the carriage at the rear or right hand end of the machine. The carriage is then pressed down by the operator through the operating handle and moved forward. This causes the upper roller and the feeding and moistening roller to grip the lower edge of the paper, and to pass it to the master copy, with its under surface moistened, and between the upper and pressure rollers, where it is printed by contact of its moistened surface with the master copy. It is then conducted by the guides 30, as it passes from the pressure rollers upward and backward to the space behind the carriage, from which it may be removed by hand or by any mechanism suitable for that purpose. The rotation of the pressure rollers is caused by the frictional contact of the under roller with the under side of the plate 10 and the upper roller with the upper side of said plate through the master copy and sheet being printed, the rollers rotating in unison. The pressure necessary to give the desired result is gauged by the operator, and this pressure may be varied within rather wide limits according to the character and condition of the master copy, the quality and thickness of the paper and the character of the printing desired. In all circumstances and under all conditions, however, the maximum printing pressure is along a line of small width across the sheets which is defined by the line of contact between the rollers through the sheet 10 and the master copy and sheet being printed, so that with close contact between the sheet being printed and the matter on the master copy, a resulting clear and sharp impression are insured.

What I claim is:

1. The herein described method or process of duplicating matter inscribed on a master sheet which consists in placing said master sheet on a resilient bed or support of relatively hard surfaced sheet material with its back to said support, moistening a face of a copying sheet and applying the same to the inscribed face of said master copy, and applying pressure progressively to the side of said support opposite the side in contact with the master copy and the side of the copying sheet opposite the side in contact with the master copy on a line substantially normal to the direction of pressure progress whereby the sheets and support are simultaneously and progressively pressed together along a line of pressure until the matter inscribed on the master copy has been impressed on the copying sheet.

2. The herein described method or process of duplicating matter carried by a master sheet which consists in placing said master sheet on a flexible bed or support of relatively hard surfaced sheet material with its back to said support, moistening a face of a copying sheet and applying said face to one face of said master copy, and applying pressure progressively to the side of said support opposite the side in contact with the master copy and to the side of the copying sheet opposite the side in contact with the master copy simultaneously and coextensively and thereby flexing said sheets and support along approximately parallel lines on a line substantially normal to the direction of pressure movement whereby the sheets and support are simultaneously and progressively pressed together

along a line of pressure until the matter inscribed on the master copy has been impressed on the copying sheet.

3. The herein described method or process of duplicating matter carried by a master sheet which consists in placing said master sheet on a flexible bed or support of relatively hard surfaced sheet material with its back to said support, moistening a face of a copying sheet and applying said face to one face of said master copy, and applying pressure progressively to the side of said support opposite the side in contact with the master copy and to the side of the copying sheet opposite the side in contact with the master copy simultaneously and coextensively on a line substantially normal to the direction of pressure movement whereby the sheets and support are simultaneously and progressively pressed together and flexed along a line of pressure until the matter inscribed on the master copy has been impressed on the copying sheet.

4. The herein described process of duplicating a master copy which consists in placing the master copy on a thin sheet of relatively hard surfaced material with its non-printing surface next to said sheet, applying a printing sheet to the printing surface of said master copy and applying pressure to said three elements simultaneously from both sides of the said thin sheet progressively and along a narrow zone extending transversely thereof.

5. In a duplicating machine, a frame, a master copy supporting member in said frame comprising a thin sheet of material, pressure rolls on both sides of said sheet and means for causing pressure between said rolls and on a master copy and printing sheet between one of them and said supporting sheet progressively on a line extending transversely of the same and a single automatic means for moistening the said printing sheet by gravity in advance of said rolls and feeding it to said rolls.

6. In a duplicating machine, a frame, a master copy supporting member in said frame comprising a thin sheet of material, pressure rolls on both sides of said sheet and means for causing pressure between said rolls on a master copy and printing sheet between one of them and said supporting sheet progressively on a line extending transversely of the same, means for feeding said printing sheet between said rolls comprising a feeding roller, means for applying moisture to said roller automatically and means for regulating and interrupting the flow of liquid to such last-named means.

7. The herein described duplicating process which consists essentially in moistening one surface of the copy sheet to be printed and passing it and the master copy sheet with the moistened surface next to the master copy between pressure rollers while interposing a thin, stiff but resilient backing or supporting sheet between one roller and the said master and copy sheets.

8. In a duplicating machine a thin, stiff but flexible sheet of material having great tensile strength and resistance to stretching strains forming a backing for the master copy and printing sheets, means for mounting said sheet to resist flexure means for mounting and maintaining said backing and master copy sheets in flatwise contact and against movement relative to each other, spaced rollers positioned in longitudinal alignment and transversely of the two last mentioned sheets one roller on each side of said sheets, means for causing pressure intermittently

between said rollers and by them on said sheets along the aligned proximate surfaces of the rollers, means for causing relative traveling movement between said rollers and said sheets, and means for interposing between said rollers and between one of them and said master copy a printing copy sheet to be printed during said movement.

9. In a duplicating machine a thin, stiff but flexible sheet of material having great tensile strength and resistance to stretching strains forming a backing for the master copy and printing sheets, means for mounting said sheet to resist flexure means for mounting and maintaining said backing and master copy sheets in flatwise contact and against movement relative to each other, spaced non-rigid rollers positioned in longitudinal alignment and transversely of the two last mentioned sheets one roller on each side of said sheets, means for causing pressure intermittently between said rollers and by them on said sheets along the aligned proximate surfaces of the rollers, means for causing relative traveling movement between said rollers and said sheets, and means for interposing between said

rollers and between one of them and said master copy a printing copy sheet to be printed during said movement.

10. In a duplicating machine a thin, stiff but flexible sheet of material having great tensile strength and resistance to stretching strains forming a backing for the master copy and printing sheets, means for mounting and maintaining said backing and master copy sheets in flatwise contact and against movement relative to each other, spaced rollers positioned in longitudinal alignment and transversely of the two last mentioned sheets one roller on each side of said sheets, means for causing pressure intermittently between said rollers and by them on said sheets along the aligned proximate surfaces of the rollers, means for causing relative traveling movement between said rollers and said sheets and rotation of said rollers through traction between said rollers and sheets, and means for interposing between said rollers and between one of them and said master copy a printing copy sheet to be printed during said movement. 5 10 15 20

DAVID WOLFSON. 25
